DESIGN FOR A BATHING CAP

Helen E. Wright, Cuyahoga Falls, Ohio, assignor
to The B. F. Goodrich Company, New York,
N. Y., a corporation of New York

Application February 15, 1934, Serial No. 50,737

Term of patent 3½ years

To all whom it may concern:

Be it known that I, HELEN E. WRIGHT, a citizen of the United States, residing at Cuyahoga Falls, in the county of Summit and State of Ohio, have invented a new, original, and ornamental Design for a Bathing Cap, of which the following is a specification, reference being had to the accompanying drawing, forming a part thereof.

The accompanying drawing shows a side elevation of a cap embodying my design.

The opposite side of the cap is a duplication of the side here shown.

I claim:

The ornamental design for a bathing cap as shown and described.

HELEN E. WRIGHT.
